UNITED STATES PATENT OFFICE

VERNON G. LEACH, OF CHICAGO, ILLINOIS, ASSIGNOR TO MODERN COAL BURNER COMPANY, OF CHICAGO, ILLINOIS, A CORPORATION OF ILLINOIS

UNDERFEED MECHANICAL STOKER

Application filed August 24, 1929. Serial No. 388,063.

This invention relates to an underfeed mechanical stoker and more particularly to the construction and arrangement of dead plates in such a stoker.

5 It is an object of this invention to provide a novel and improved construction of dead plates wherein the assembling and removing of the dead plates is greatly facilitated.

It is a further important object of this invention to provide dead plates in the form of bars of heavy and rugged construction and provided with cooling ribs or fins, whereby tendencies to warp and crack are eliminated.

Other and further important objects of 15 this invention will be apparent from the disclosures in the specification and the accompanying drawings.

This invention (in a preferred form) is illustrated in the drawings and hereinafter 20 more fully described.

On the drawings:

Figure 1 is a transverse sectional view of 25 a furnace setting illustrating the installation of an underfeed mechanical stoker of my invention.

Figure 2 is a fragmentary top plan view of the stoker.

Figure 3 is a longitudinal sectional view of one form of dead plate.

30 Figure 4 is a longitudinal sectional view of another form of dead plate.

As shown on the drawings:

The reference numeral 1 indicates as a 35 whole a furnace housing comprising a lower wall 2 of masonry and side walls 3 extending thereabove. An underfeed mechanical stoker, indicated as a whole by the reference numeral 4, is adapted to be partially housed within the furnace housing 1. Said stoker

40 4 comprises a retort 5, a conveyor 6 for feeding and distributing coal or other fuel in said retort, tuyère blocks 7 and ash and slag receiving surfaces 8 and 9 positioned alongside the rows of tuyère blocks 7 and spanning 45 the space between said tuyère blocks and the walls 2.

Front and rear plows 10 and 11, respectively, from the ends of the built-up retort 5, which includes the tuyère blocks 7 positioned 50 along the lateral upper edges of said retort.

Each of said ash and slag receiving surfaces 8 and 9 comprises a plurality of dead plates 12, 13 and 14 which are of relatively narrow, rectangular construction cast in the form of bars. Certain of said dead plates, as for instance, the dead plates 12, are formed with two male joint forming elements 15 and 16 comprising simply downturned flanges formed along the lateral edges of said dead plates. The inside flange 15 is adapted to 55 rest in and be received by a groove 17 formed by a series of registering grooves extending transversely along the upper rear edges of the tuyère blocks 7 and end pieces 10 and 11.

It is an object of this invention to provide dead plates 13, assuming that 60 there are three dead plates on each side of the retort as shown, are provided with female joint forming elements 19 along their inner lateral edges and male joint forming elements 20 along their outer lateral edges. Each of 65 the female joint forming elements 19, includes a longitudinally extending groove 21 for receiving the male joint forming element 16 of the dead plate 12. The dead plates 12 and 13 are provided with longitudinally extending 70 dependent ribs or fins 22 and 23, respectively, to serve both for reinforcing said dead plates and for cooling purposes. Longitudinal grooves 39 in the upper surfaces of the dead plates form guides for the bar used in 75 removing ashes and slag. The ends of said dead plates 12 and 13 are further provided with downturned flanges 24 and 25, respectively, adapted to rest directly upon the lower end walls (not shown) of the furnace housing and be sealed thereto, as by means of cement in a similar manner to the cement seal 80 40 at the sides.

Each of the dead plates 14 forming the outer edge of the ash and slag receiving surfaces, is provided with a female joint forming member 26 having a longitudinal groove 27 for receiving the male joint forming member 20. The joints thus formed between the various dead plates 12, 13 and 14 are 85 preferably further sealed against the leakage of air into the upper space above said dead plates by means of a suitable cement laid within the joint grooves 21 and 27, and for 90 this purpose the edges of the male forming 95 100

elements may be squared off, as at 21, to provide a space for the cement.

It will be appreciated that by making the dead plates in the form of bars extending the full length of the retort 5 and of relatively narrow dimensions, the setting of these dead plates is greatly facilitated. Inasmuch as the inside dead plates 12 being formed with two male joint forming elements 15 and 16 merely rest in the grooves 17 in the tuyère blocks 7 and in the grooves 21 of the next adjoining dead plates 13, said dead plates 12 may be easily removed for the purpose of removing or replacing any of the tuyère blocks 7, without necessitating the removal of all of the dead plates and therefore with a minimum of labor.

I am aware that many changes may be made and numerous details of construction may be varied through a wide range without departing from the principles of this invention, and I, therefore, do not purpose limiting the patent granted hereon otherwise than necessitated by the prior art.

25 I claim as my invention:

1. In an underfeed stoker, the combination of a plurality of tuyère blocks in assembled relation, each having a registering groove formed along an edge, dead plates provided with male and female joint forming elements associated therewith, the dead plate adjacent the grooved edge of the tuyère block having an upstanding and reversely directed portion forming a ridge and a male joint forming element along one of its longitudinal edges, entered in the groove of the tuyère block, and having a second upstanding and reversely directed portion forming a ridge and a male joint forming element along its other longitudinal edge for cooperation with a female joint forming element on the next adjacent dead plate.

2. A dead plate for a furnace, the said dead plate comprising a relatively narrow member having a pair of spaced upstanding and reversely directed curved longitudinal edge portions defining spaced apart ridges and a channel therebetween.

3. A dead plate for a furnace, said dead plate comprising a relatively narrow member having an upstanding ridge formed along a longitudinal edge and a curved female joint forming portion formed along the same edge.

4. A dead plate for a furnace, said dead plate comprising a relatively narrow member having an upstanding ridge formed along a longitudinal edge and an integrally connected curved female joint forming portion along the same edge, an upstanding ridge formed along its other longitudinal edge, and a downwardly curved male joint forming portion along that edge, a channel being formed between the upstanding ridges.

5. A dead plate for a furnace, said dead plate comprising a relatively narrow member

having an upstanding ridge formed along a longitudinal edge and a downwardly curved male joint forming portion formed along the same edge.

6. A dead plate arrangement for a furnace, comprising a plurality of relatively long and narrow members in interfitted connection with each other, said members having upstanding and reversely directed curved longitudinal edge portions forming ridges and providing male and female joint forming means for cooperative association between the members, and providing inclined abutting surfaces defining channels on the working surface of the arrangement.

In testimony whereof I have hereunto subscribed my name at Chicago, Cook County, Illinois.

VERNON G. LEACH.
